PICTURE FRAME

Maurice Spertus, Highland Park, Ill.

Application April 30, 1956, Serial No. 41,316

Term of patent 3½ years

(Cl. D29—20)

Fig. 1 is a front elevational view of a picture frame, showing my new design;

Fig. 2 is a side elevational view;

Fig. 3 is an end elevational view; and

Fig. 4 is a sectional view taken along the line 4—4 of Fig. 1.

The dominant features of the design reside in the portion shown in full lines.

I claim:

The ornamental design for a picture frame, substantially as shown and described.
